BLACK-OUT LIGHT FOR VEHICLES

Wagn Trautner, Hamilton, Ohio, assignor to The
K-D Lamp Company, Cincinnati, Ohio, a cor-
poration of Ohio

Application August 11, 1942, Serial No. 454,411

9 Claims. (Cl. 177—329)

My invention relates to structures for use on vehicles, including both civilian and military vehicles, during blackouts or other conditions precluding the use of illuminants visible from the air. These structures are used for a variety of purposes, and the particular mode of use does not constitute a limitation on my invention. I will describe my invention in connection with a structure which may be employed as a combined tail light and stop signal for vehicles.

In such structures it has been recognized that limited visibility is a desideratum, and this has been obtained, in general, by the use of a filter to control either the intensity or the color value of the light, or both, a mask to limit the area of light emission, and a front lens of some sort to protect the other elements. In some cases, the light or signaling device must be of such character as to give an indication to the observer of the distance of the device. This is usually accomplished by providing spaced perforations in the masking member so related to each other that within a given distance they will appear as separate light sources, whereas, from a greater distance, they will merge into one. Also, it is sometimes desirable that the signal give to the observer an indication of his angle of view. This is usually accomplished by providing one or more perforations in the masking device, which perforations have a shape varying vertically. Such a masking device is used in connection with a front lens member of restricted effective area and spaced from the mask member a given distance. The full area of the perforations in the mask member thus becomes visible only within a narrow angle. A departure from this angle, either up or down, results in the cutting off of the visibility of a portion of the perforations, thereby giving an indication of angular position. In my device all of these effects may be obtained as desired.

There has also been recognized that whatever construction is adapted must have the characteristics of being sealed against the entrance of dirt, dust and mud; and this is an official requirement for military vehicles. Dust, dirt and mud can, of course, accumulate on the outside of the lamp housing and on the outside of the lens element. But when this happens, it can usually be removed by a simple wiping operation. It is essential that foreign substances shall not enter the housing or get between the lens element and the mask or cover, or obscure the filter.

The fundamental object of my invention is the provision of a structure of very much simplified and cheaper form, while having the advantages

of former structures and meeting the requirements hereinabove set forth. It is an object of my invention to provide adequate sealing with fewer and simpler parts, and in general, to provide a unitary structure comprising the lens elements, mask elements, and filter elements, which are required for the purpose set forth, together with baffle means. It is an object of my invention to provide a structure in which the failure and replacement of one or more of the bulbs does not require the replacement of any other parts. It is an object of my invention to provide a sealed, unitary structure, as hereinabove mentioned, in which the structure acts as a sealing element for the lamp housing. It is an object of my invention to provide a structure in which disassembly, replacement, and reassembly are facilitated under conditions of darkness and in which the proper orientation of the various parts is assured. It is an object of my invention to provide the necessary elements in a simplified and cheapened form.

These and other objects of my invention, which will be set forth hereinafter or will be apparent to one skilled in the art upon reading this specification, I accomplish by that certain construction and arrangement of parts of which I shall now describe an exemplary embodiment.

Reference is made to the drawing wherein:

Fig. 1 is a front elevational view of the so-called unitary assembly.

Fig. 2 is a plan view of the unitary assembly with certain parts in section.

Fig. 3 is a vertical sectional view of the structure itself taken along the line 3—3 of Fig. 1.

Fig. 4 is a front elevational view of the completed device.

Fig. 5 is an exploded view of the parts making up the unitary assembly.

Fig. 6 is a perspective view of a combined mask and filter element which I prefer to use.

The structure of the housing of my device may be widely varied as will be understood. In its exemplary embodiment, it comprises a cup-shaped housing member 1, to the rear of which is attached another cup-shaped housing member 2.

One purpose of this form is to enable me to attach a bracket 4 to the housing member 2 by means of a grommet 3, so as to provide a swiveled construction. The bracket 4 will be attached to the vehicle in any suitable way, as for example, by means of another bracket pivoted to the bracket 4 and providing for such adjustment as will bring the axis of the housing to the horizontal. The housing may be swiveled on the bracket 4 to orient the transparent lens

portions. Socket devices 5 may be mounted on the bottom of the housing member 1. The electrical connections for these sockets may pass through the grommet, as shown. Incandescent lamps 6 and 7 may be placed in the sockets.

The housing member 1, at its open end, may conveniently be terminated as at 8 in a rolled bead, or in some other configuration providing a shoulder against which the unitary assembly, next to be described, may be placed. The structure is completed by a cap 9 which covers the unitary assembly and is suitably perforated to disclose portions of the lens element. The cap engages snugly over the housing 1 and may be held in place in any suitable way. It is possible to fasten the cap to the housing 1 by means of screws passing through the flange of the cap and engaged in threaded openings in the housing. I prefer to employ fastening means hereinafter described.

My unitary assembly comprises a lens element, one or more hollow bodies which are preferably combined masking and filtering means, preferably a gasket, and a metal mounting plate of generally cup-shape, perforated for the passage of the masking and filtering means. The metal mounting plate, in the final form of the unitary assembly, will have its edges crimped over the lens element, thereby serving to hold the parts together. The mounting plate, in structures employing more than one illuminant, will be provided with baffles, as may be required.

The lens and filter elements are of translucent or transparent substance and may be made of glass, although I prefer to make them of some translucent plastic which is non-brittle and not subject to shattering. The lens element is a disk-like body 10, having on its front surface certain protuberances 11 and 12 which are designed to form the effective lens surfaces, and to extend through perforations in the cap 9. The rear surface of the lens element may be provided with recesses 13 and 14 to accept the edges or edge flanges of the masking and filtering elements next to be described. The extreme edge of the lens element may be provided with a groove 15 to coat with the gasket. While I have spoken of the element 10 as a lens element, it will be understood that for most uses, it is not designed to refract light, but on the contrary, will have parallel, plane surfaces. Where such a thing is desired, however, these surfaces may be non-parallel, or may be curved to produce refraction.

While it is possible to employ separate filtering elements and masking elements, such as perforated metal plates, I prefer to employ a simplified structure, as herein illustrated. My filtering elements are preferably made in the shape of hollow bodies 16 or 17 of generally cup-shape. Their open ends may be provided with a peripheral flange 18. Since these elements are to serve the combined purposes of a mask and a filter, I provide a way of coating the inside surfaces of the hollow bodies with an opaque substance, except over the areas through which light is to pass. One of such areas is indicated at 19 in Fig. 6, and I have found that if I mould this area in the form of a depression in the bottom of the hollow body 16, I can easily locate in it a template or plug, and then spray the opaque substance over the remainder of the inside surfaces of the hollow body 16. The particular shape and number of translucent areas 19 in the filter do not constitute a limitation on my invention. In the exemplary embodiment herein disclosed, I

have shown a stop light section having one odd-shaped, translucent area and a tail light section having two pairs of spaced, odd-shaped, translucent sections for purposes already set forth. The areas 11 and 12 of the lens element lie opposite the translucent area or areas of the mask and filter elements.

The substance of the filters will be translucent; but the filters may, if desired, be clear, or may have a diminished light transmitting characteristic to cut down the intensity of the illumination. Also, they may be colored as desired in order to restrict the illumination to a given section of the spectrum.

15 The next element in my unitary assembly is a gasket means, indicated at 20. This may, if desired, be of rubber or other resilient material, but I have found that it may be more cheaply made of paperboard or other fibrous substance, 20 with or without a waterproof binder. Its peripheral shape will be that of the lens element 10, but it will be perforated, as shown, to accept the hollow bodies 16 and 17.

The mounting plate is a cup-shaped structure 25 having a bottom 21 and peripheral walls 22. The bottom will be perforated, as at 23 and 24, to accept the hollow bodies 16 and 17, and the metal of the mounting plate may conveniently be up-set about the edges of the perforations, 30 as shown. Where the illuminating device contains more than one incandescent bulb, a baffle or baffles are required. Where the shape of the filter elements permits, these baffles may be struck up from the body of the mounting plate. 35 Otherwise, they may be separately formed and attached to the mounting plate as by spot welding, riveting, or the like.

The several elements forming the unitary assembly are put together, as will be clear from 40 Fig. 2, and in the order shown in Fig. 5. When this is accomplished, the edges of the walls 22 of the mounting plate are crimped over the lens element, as at 25 in Fig. 2, thus providing a unitary structure which has now been fully described 45 as to its essentials, excepting that I prefer to form perforations 26 and 27 therethrough. The cap element 9 will be similarly perforated, as well as being perforated, as shown, for the lens portions 11 and 12. The unitary assembly may be 50 placed in the cap 9 and the edges of the cap passed over the open end of the housing member 1. When this is accomplished, the unitary assembly will lie tightly against the shoulder 8 on the housing. Screws 28 and 29 may be 55 passed through the perforations in the cap and unitary assembly, and may be threaded into brackets 30 affixed to the housing member 1. It will be noted that the perforations 26 and 27 lie to one side of a diameter of the unitary assembly, or are otherwise asymmetrically placed 60 so as to insure the proper orientation of the cap 9 and the unitary assembly on the housing, and to facilitate putting the parts together in the proper orientation under conditions of darkness.

It will be noted also that the construction is 65 a sealed construction. Dirt cannot enter the housing, nor the spaces between the lens and filter elements. External surface dirt may 70 readily be wiped from the exposed lens portions 11 and 12. Yet, the structure may easily be taken apart, and the bulbs 6 and 7 are replaceable without requiring the substitution of new lens or filter elements.

75 My invention is not limited as to the number

of separate filter elements which may be employed in connection with a given device or as to the number of incandescent lamps which it may contain.

Modifications may be made in my structure without departing from the spirit of my invention. Having thus described my invention in an exemplary embodiment, what I claim as new and desire to secure by Letters Patent is:

1. In a structure of the class described comprising a housing, a unitary sealed assembly including a lens element, a cup-shaped filter element having an outwardly extending peripheral flange at its open end and a mounting plate for holding the lens element and the filter element in sealed assembly, the said mounting plate having a cup-shaped body perforated to accept the said filter element and peripheral walls crimped over the edge of the lens element.

2. In a structure of the class described, a housing containing illuminating means, a cap, and a unitary assembly comprising a lens element, a plurality of filter elements of lesser cross-sectional area and a mounting plate, said filter elements being in the form of cup-shaped bodies with peripheral flanges at their open ends, said mounting plate being perforated to accept said hollow bodies in side-by-side relationship, the said mounting plate having peripheral walls encompassing and crimped over the edges of said lens whereby to fasten said lens and said filter elements together into a unitary assembly.

3. The structure claimed in claim 2 wherein said mounting plate carries a baffle, said housing containing at least two incandescent bulbs, one located on each side of said baffle.

4. The structure claimed in claim 2 wherein said mounting plate carries a baffle, said housing containing at least two incandescent bulbs, one located on each side of said baffle, said unitary assembly including a gasket, said cap being perforated to disclose portions of said lens element, said housing having a shoulder against which said unitary assembly engages, and means in connection with said cap for fastening said cap to said housing whereby to provide a sealed construction.

5. The structure claimed in claim 2 wherein said mounting plate carries a baffle, said housing containing at least two incandescent bulbs, one located on each side of said baffle, said unitary assembly including a gasket, said cap being perforated to disclose portions of said lens element, said housing having a shoulder against which said unitary assembly engages, and means in connection with said cap for fastening said cap

5 to said housing whereby to provide a sealed construction, said last mentioned means including means for determining the orientation of said cap and the said unitary assembly with respect to said housing.

6. A unitary assembly for the purpose described comprising a lens element, a plurality of filter and masking elements, each being in the form of a cup-shaped body with a peripheral flange at its open end, a gasket perforated to receive the hollow bodies of said filter and masking elements, a mounting plate in the form of a cup-shaped body having a bottom perforated to receive said masking and filter elements, and peripheral walls enclosing said gasket and said lens and being crimped over the outer peripheral surfaces of said lens element.

7. The structure claimed in claim 6 wherein the inner surface of said lens element is recessed 20 to receive the edges of said masking and filter elements, the depth of the recesses being substantially the depth of the said flanges on said masking and filter elements, the said lens having portions of its outer surface lying opposite said masking and filter elements extended forwardly.

8. The structure claimed in claim 6 wherein the inner surface of said lens element is recessed 30 to receive the edges of said masking and filter elements, the depth of the recesses being substantially the depth of the said flanges on said masking and filter elements, the said lens having portions of its outer surface lying opposite said masking and filter elements extended forwardly, said masking and filter elements having recesses in their bottoms demarcating restricted translucent areas for the passage of light, the remainder of their inner surfaces being covered with an opaque substance.

40 9. The structure claimed in claim 6 wherein the inner surface of said lens element is recessed to receive the edges of said masking and filter elements, the depth of the recesses being substantially the depth of the said flanges on said 45 masking and filter elements, the said lens having portions of its outer surface lying opposite said masking and filter elements extended forwardly, said masking and filter elements having recesses in their bottoms demarcating restricted translucent areas for the passage of light, the remainder of their inner surfaces being covered with an opaque substance, and said mounting plate bearing a rearwardly extending baffle located between 50 said masking and filter elements.

55 WAGN TRAUTNER.
